UNITED STATES PATENT OFFICE.

WALTER F. SAFFORD, OF PROVIDENCE, RHODE ISLAND.

PARING-KNIFE.

1,330,820.

Specification of Letters Patent.

Patented Feb. 17, 1920.

Application filed July 2, 1919. Serial No. 308,167.

To all whom it may concern:

Be it known that I, WALTER F. SAFFORD, a citizen of the United States, residing at Providence, in the county of Providence and 5 State of Rhode Island, have invented new and useful Improvements in Paring-Knives, of which the following is a specification.

This invention relates to certain new and useful improvements in paring knives, and 10 the primary object thereof is to provide a paring knife which is especially adapted for use with the well-known safety razor blades.

A further object of the invention is to provide a paring knife wherein the blade 15 can be easily and quickly removed and replaced by a new blade, and to also provide means for positively holding the blade in clamped operative position in the handle, or holder provided for the blade.

20 Still further the invention aims to provide a novel inexpensive and efficient holder for the blade and means to connect same to the handle.

Further and other objects will later appear and be set forth in the course of the 25 following description.

In the drawings:

Figure 1, is a rear view of the device;

Fig. 2, is a front view thereof, and

30 Fig. 3, is an enlarged section on line 3—3 of Fig. 1.

In proceeding in accordance with the invention, a preferably wooden handle 1, is employed, of the shape depicted in the drawings. To one end of the handle the holder is secured, the latter embodying a neck 2 formed with wings 3, providing a socket-like portion in which one end of the handle is received. In order to positively 35 secure the neck to the handle, teats 4, are struck-out from the neck to extend into the wood body of the handle, thereby providing a positive means of anchorage, securing the holder against movement in an obvious 40 manner.

The opposite end of the holder is shaped to provide an eye cutter, or knife portion 5, of somewhat V-form, while between the neck and the portion 5, the sides of the 45 holder are inturned or flanged at 6 and 7, the flange 7, being of somewhat arched formation so as to provide a clamping edge portion 8, to bear against the safety razor blade 9. The back edge of the blade 9, is 50 shown as having the usual reinforced back- 55 ing 10, which is received in the space pro-

vided by this arching of the flange 7, so that the backing will abut the part 11, of the flange. The flange or the curled portion 6, provides a guiding or gage part which 60 engages the object being pared and has the cutting edge of the blade 9, disposed opposite thereto, the cutting edge being exposed through a slot 12, formed by striking out a part 12^a, the latter part being disposed parallel to the portion 6, and acting to reinforce 65 and strengthen the holder as is obvious. The part 12^a, further serves as a guard for the cutting edge of the blade.

The entire holder is made of a single sheet 70 of metal, which simplifies the production and the cost thereof. The blades can be renewed by simply forcing same past the eye cutter 5, and a new blade can be as easily inserted, the blades being held by the frictional clamping action of the part 8. In addition both the wings 3 forming the anchoring socket and the clamp 8, as well as 75 the gage 6, are all formed by bending the sides of the sheet metal blank or body inwardly as shown in Fig. 1, thus simplifying the manufacture since but a single bending operation is thus necessitated.

Having thus described my invention, what I claim as new and desire to secure by 80 Letters Patent is—

1. In a paring knife, a handle, a holder having a socketed portion receiving one end of the handle and having side flanges extending toward each other, a struck-out part 90 forming a slot, said part being disposed adjacent one of said side flanges, the other side flange being formed to provide a clamp, and a blade engaged between said clamping flange and the body of the holder and being 95 held with its cutting edge disposed in the slot and with its back edge engaged with the outer side portion of the clamping flange.

2. A paring knife composed of a holder having its sides turned inwardly, the turned portions at one end jointly forming a handle socket and those at the opposite end a clamp and gage, and a blade engaged with the clamp.

In testimony whereof I have signed my 105 name to this specification in the presence of two subscribing witnesses.

WALTER F. SAFFORD.
